UNITED STATES PATENT OFFICE.

LARS H. VOLD, OF WESTVILLE, NEW JERSEY, ASSIGNOR TO WILLIAM SELLERS & COMPANY, INCORPORATED, OF PHILADELPHIA, PENNSYLVANIA, A CORPORATION OF PENNSYLVANIA.

LOADING AND UNLOADING APPARATUS.

1,072,533.

Specification of Letters Patent.

Patented Sept. 9, 1913.

Application filed April 16, 1913. Serial No. 761,552.

To all whom it may concern:

Be it known that I, LARS H. VOLD, a citizen of the United States, residing at Westville, county of Gloucester, and State of New Jersey, have invented a new and useful Improvement in Loading and Unloading Apparatus, of which the following is a full, clear, and exact description, reference being had to the accompanying drawings, which 10 form a part of this specification.

My invention is applicable to punching machines and other kinds of machines where it is desirable to bring the work to the machine and to remove it after completion with ease and in the quickest possible time. In the case of a punching machine, for which the invention is especially adapted, the work enters on one side or at the rear of the machine, passes under the punches and thence to the other side or front of the machine, from which it is removed and the work carrying apparatus run back into the first position to receive new work. Such a machine is set forth in my 25 Patent No. 833,811, dated October 23, 1906.

Time is required to place the new work on the carrying apparatus and to remove it after completion. During these intervals the punching machine is necessarily idle.

The object of my invention is to assemble the work ready for the carrying apparatus at one side of the machine, transfer it to the carrying apparatus in the shortest possible time, and after completion to remove it immediately from the carrying apparatus, so that the latter can immediately return for the new work which is to be placed in position, thereby permitting the almost continuous operation of the punch. To accomplish 40 this object I have devised an apparatus, one preferred embodiment of which is shown in the accompanying drawings, wherein—

Figure 1 is a general plan view of the apparatus. Fig. 2 is an enlarged side view of 45 a punching machine and a portion of the work table. Fig. 3 is an enlarged cross section on the line 3—3 of Fig. 1. Fig. 4 is a similar section on the line 4—4 of Fig. 1, showing two of the loading lifting jacks in their raised position. Fig. 5 is a detail view of one of the unloading lifting jacks.

I have not illustrated the punching machine *a* in detail, as the specific construction thereof forms no part of my invention.

It is sufficient to say that the table for carrying the work through the machine comprises longitudinally movable rack bars 10 carried on stationary rollers 9, and stationary rollers 11 for supporting and guiding the work. These rack bars are actuated by 50 suitable traversing mechanism (such, for example, as the gear 8, as is set forth fully in Patent No. 833,811 hereinbefore referred to) in the direction of their length, being first moved step by step in the direction of 55 the arrow, Fig. 1, carrying the work with them through the punching machine, and then, after the punching operation is completed and the work is removed, returned to their original position to receive new work. 60

In carrying the work through the punching machine as above described, the work is engaged, at either its front end, or at both ends, by grippers carried by the rack-bars. Any suitable gripping mechanism may be 65 employed. As an example I have shown a cross-beam 12, mounted on the rack-bars in front of the punching machine, and carrying a number of gripping devices 13, similar to those disclosed in said Patent No. 80 833,811, adapted to be secured to the front ends of the work. For some kinds of work a similar beam and similar gripping devices may be arranged at the rear end, the beam being adjustable along the rack bars so that 85 it can be set to suit different lengths of work; such additional beam and gripping devices not, however, being shown, as they are known in the art and form no part of, and are not necessarily employed in connection with, the present invention. It is obvious that in traversing the rack bars 10, the 90 cross-beam 12 and grippers 13 will travel with them and draw the work through the machine.

It will be observed that the work-supporting rollers 11 are arranged both in front of, and at the rear of, the punching machine, in a plurality of sets, the rollers of each set being mounted in a common support 14 extending transversely of the apparatus. Each support 14 at the rear or receiving end of the apparatus carries also a set of rollers 15 and a set of lifting jacks 16. Each support 14 at the front or discharge end of the 100 apparatus carries a set of rollers 150 and a set of lifting jacks 160. The jacks 16 and 160 may be raised and lowered by any ap-

5 appropriate means. At the rear of the apparatus, and at one side of the work table, is the loading table *b*, and at the front of the apparatus, and at one side of the work table, is the unloading table *c*. The loading table and unloading table are similar in construction, each comprising a series of supports 18 carrying sets of transfer rollers 19 in alignment with the sets of rollers 15 or 150 of the 10 work table. The transfer bars 20 have racks driven by gears 190.

15 In operation, the work *x* is placed on the transfer bars 20 of the loading table *b*, and the shaft 21 is turned to move the loading transfer bars from the rollers 19 to the aligning rollers 15 at the receiving end of the work table. The work is thus properly aligned with the machine but at a higher level. The lifting jacks 16 are then raised 20 to lift the work off the bars 20 and above the rollers 11, the bars 20 are returned to their original position, the jacks 16 are lowered until the work rests on the rollers 11, the work is engaged by the grippers 13, the 25 rack bars 10 are advanced step by step, conveying the work through the punching machine to the discharge end of the work table, the grippers are released, the lifting jacks 160 at the discharge end of the work table 30 are raised to lift the work off the rollers 11, the transfer bars 20 of the unloading table *c* are moved from the rollers 19 to the rollers 150, the lifting jacks 160 are lowered and the work deposited on the unloading transfer bars, which are returned to the rollers 35 19, and the rack bars 10 are returned to their starting position ready to receive new work.

40 If the work to be punched consists of plates, no special construction of jacks is necessary, but if angle bars are to be punched, it is necessary to bring them into the proper punching position with one leg vertical and the other horizontal. It is desirable to handle them in groups of two. The drawings show four such groups or 45 eight angles. They are assembled on the transfer bars 20 of the loading table *b*, as indicated in Fig. 3, resting on their edges 50 with the apices of the angles up. They are grouped about centering marks *y* on the transfer bars. Each lifting jack has a recess in its head, into which recess one leg of each angle bar will drop as the jack rises 55 until the horizontal legs of the angles rest on the head of the jack, so that when the jack is lowered the angles will rest on the rollers 11 in the proper position for punching. In the case of heavy angles no further 60 precautions are necessary, but when the angles are light and of small dimensions it is necessary to limit the movement of the inside legs. This I do by forming a central partition 17 at the bottom of the recess 65 in the jack head, having a pointed top to

guide the angles into their proper places. When a jack 16 is lifted, the inside legs of the angles *x* drop into the depressions on either side of the central partition 17 until the 70 outside legs of the angles rest on or over the overhanging upper faces of the jack, as shown in Fig. 4. After the transfer bars 20 are retracted, the jacks are lowered to bring the horizontal legs of the angles to rest on the supporting rolls 11. The angles are thus set in the proper position and the proper location for punching. In Fig. 5 is 75 shown the position of the angles after they are engaged and lifted by the unloading jacks 160 preparatory to lowering the angles and depositing them upon the unloading transfer bars. The unloading jacks 160 are provided with the central transverse recess, but without the separating partition.

80 It will be understood that while work is traveling through the punching machine, time is afforded to allow new work to be properly arranged on the loading table and punched work to be removed from the unloading table, so that, at the conclusion of 85 the punching operation, new work is arranged ready for transfer to the work table as soon as the rack bars 10 are returned to the receiving position.

Having now fully described my invention, 90 what I claim and desire to protect by Letters Patent is:

1. In an apparatus of the character described, the combination with a machine for operating upon the work, of a work-carrier comprising means to support and guide the work and move it through the machine, a transfer table arranged at one side of the path of the work, said table comprising transversely extending work-supporting bars, means to move the transfer bars back and forth across the path of the work, and lifting jacks in the path of the work adapted to engage the work and transfer it from the transfer bars to the work-supporting means, or vice versa. 100

2. In an apparatus of the character described, the combination with a machine for operating upon the work, of a work-table comprising supporting rollers and means to 105 convey the work through the machine, a transfer device comprising transversely extending bars and means to move them in the direction of their length into and out of the path of the work, and lifting jacks adapted 115 to engage the work and transfer it from the transfer bars to the supporting rollers, or vice versa. 120

3. In an apparatus of the character described, the combination with a machine for 125 operating upon the work, of a work-carrier comprising means to support and guide the work and move it through the machine, a loading table and an unloading table arranged respectively at the rear and at the 130

- front of the machine at one side of the path of the work, each table comprising transversely extending work-supporting transfer bars, means to move the transfer bars 5 back and forth across the path of the work, and lifting jacks in the path of the work adapted to engage the work and transfer it from the transfer bars to the work-supporting means, or vice versa.
- 10 4. In an apparatus of the character described, the combination with a machine for operating upon the work, of a work-table comprising supporting rollers arranged at the rear and at the front of the work and 15 means to convey the work through the machine, a loading device and an unloading device each comprising transversely extending transfer bars and means to move them in the direction of their length into and 20 out of the path of the work, and lifting jacks at the rear of the machine adapted to engage the work and transfer it from the loading transfer bars to the supporting rollers, and lifting jacks in front of the machine 25 adapted to engage the work and transfer it from the supporting rollers to the unloading transfer bars.
5. In an apparatus of the character described, the combination with a machine for 30 operating upon the work, of work-conveying bars extending from rear to front through the machine, a number of sets of supporting and guiding rollers rotatable on transverse axes, a number of sets of rollers rotatable 35 on longitudinal axes, a number of sets of lifting jacks, said rollers and jacks arranged behind the machine, a number of transversely extending loading transfer bars adapted to be moved in the direction of 40 their length onto the second-named sets of rollers to convey the work over the lifting jacks, whereby the latter may be lifted and lowered to remove the work from the loading transfer bars and deposit it on the supporting rollers, and means to traverse the 45 loading transfer bars.
6. In an apparatus of the character described, the combination with a machine for operating upon the work, of work-conveying 50 bars extending from rear to front through the machine, a number of sets of supporting and guiding rollers rotatable on transverse axes, a number of sets of rollers rotatable on longitudinal axes, a number of sets of lifting jacks, said rollers and jacks arranged in front of the machine, a number of transversely extending unloading transfer bars adapted to be moved in the direction of 55 their length onto the second-named sets of rollers, whereby the lifting jacks may be lifted and lowered to remove the work from the supporting rollers and deposit it on the unloading transfer bars, and means to traverse the unloading transfer bars.
- 60 7. In an apparatus of the character de- 65
- scribed, the combination with a machine for operating upon the work, of work-conveying bars extending from rear to front through the machine, a number of sets of supporting and guiding rollers, rotatable on transverse axes, arranged in front of and behind the machine, a number of sets of transfer-bar engaging rollers, rotatable on longitudinal axes, arranged in front of and behind the machine, a number of sets of lifting jacks 70 arranged in front of and behind the machine, a number of transversely extending loading bars arranged behind the machine and means to reciprocate them in the direction of their length into and out of supported relation with the rear transfer bar engaging rollers and into and out of operative relation with the rear lifting jacks, and a number of transversely extending unloading bars arranged in front of the machine and means to reciprocate them in the direction of their length into and out of supported relation with the front transfer bar engaging rollers and into and out of operative relation with the front lifting jacks. 75
- 80 8. In an apparatus of the character described, the combination with a machine for operating upon the work, of a work-table comprising means to support and guide the work and move it through the machine, a 85 transfer table arranged at the rear of the machine at one side of the path of the work, said table comprising transversely extending work-supporting bars, means to move the transfer bars back and forth in the direction of their length across the path of the work, and lifting jacks arranged back of the machine and adapted to engage the work and transfer it from the transfer bars to the work-supporting means or vice-versa, said 90 lifting jacks having in their heads recesses extending longitudinally of the path of the work, and adapted to receive angularly disposed members of the work. 95
- 100 9. In an apparatus of the character de- 105
- scribed, the combination with a machine for operating upon the work, of a work-table comprising means to support and guide the work and move it through the machine, a loading table and an unloading table arranged respectively at the rear and at the front of the machine at one side of the path of the work, each table comprising transversely extending work-supporting transfer bars, means to move the transfer bars back 110 and forth across the path of the work, and lifting jacks in the path of the work adapted to engage the work and transfer it from the transfer bars to the work-supporting means, or vice versa, said lifting jacks having in 115 their heads recesses extending longitudinally of the path of the work and adapted to receive angularly disposed members of the work. 120
- 125 10. In an apparatus of the character de- 130

scribed, the combination with a machine for operating upon the work, of a work-table comprising means to support and guide the work and move it through the machine, a loading table arranged at the rear of the machine at one side of the path of the work, said table comprising transversely extending work-supporting transfer bars, means to move the transfer bars back and forth in the direction of their length across the path of the work, and lifting jacks arranged back of the machine and adapted to engage the work and transfer it from the transfer bars to the work-supporting means, said lifting jacks having in their heads recesses

extending longitudinally of the path of the work, and similarly extending partitions each projecting up from the center of the base of a recess and dividing the latter into two depressions adapted to receive adjacent angularly disposed members of two pieces of work.

In testimony of which invention, I have hereunto set my hand, at Philadelphia, on this 14th day of April, 1913.

LARS H. VOLD.
